UNITED STATES PATENT OFFICE.

JEREMIAH E. BROWN, OF BROOKLYN, NEW YORK.

SWING.

Application filed April 28, 1922. Serial No. 557,207.

To all whom it may concern:

Be it known that I, JEREMIAH E. BROWN, a citizen of the United States, residing at Brooklyn, in the county of Kings and State of New York, have invented certain new and useful Improvements in Swings, of which the following is a specification.

This invention relates to swings of the type commonly used as an amusement device for children the main object being the provision of a swing designed to seat a number of infants side by side, and in individual chairs so that they can be removed from the swing without disturbing the others.

Another object is to provide a central seat on the swing for the use of a maid or caretaker of the infants, and means for starting the swing to oscillate, to and fro, is provided with the seat and is operated by the feet of the person.

These and other objects will become apparent in the description below in which similar characters of reference refer to like named parts in the drawing, in which—

Figure 1 represents an end elevational view of the swing and is shown in a position of rest.

Figure 2 is a front elevational view of the same.

Figure 3 is a perspective view of part of the swing platform showing the recesses in which the detachable seats are mounted.

Describing the drawing in detail, the numeral 1 indicates the end support beams which are reinforced by a similar member 2. Each of said beams 1 form a base for the vertical columns 3 and are connected to each other by a truss beam 4.

End braces 5 and side braces 6 support the columns 3 and provide a rigid means for preventing excessive swaying of the said column while the swing is being used.

A swing platform 7 is suspended from truss 4 by stout ropes 8 which have metal rings 9 at the ends and are provided for freedom of movement and reducing friction to a minimum.

Said platform is of hollow construction and consists of longitudinal side frames 9' joined to each other by the spacers 10 which are provided with eyelets 12 to which are secured the cradle ropes 13. The lower internal edges of frames 9' have flanges 14 which

receive the lower portions of detachable seats 15. The central seat, indicated by the numeral 16, is the operator's and has a vertical wall 17 secured to the front platform frame 9'. A platform 18 attached to the lower end of wall 17 has a foot pedal board 19 pivotally mounted thereon between the brackets 20.

A pair of coil springs 21 are suspended from truss 4 above the operator's seat 16, the lower end having a chain 22 secured thereto. The chain being securely attached to the free end of foot pedal 19.

An awning 23 attached to a roller 24 is suspended above the swing platform 6 and can be rolled upon roller 24 or retained in the position shown by Figures 1 and 2. Said roller is mounted, as shown, between the brackets 25 and is of the usual spring tension type, this enabling the device to be operated during inclement weather, or otherwise forming a sunshade.

The swing is especially applicable for use in parks or playgrounds where numbers of small children are wont to spend their time, and can be installed in any location desired after the latter has been leveled.

In use the children are comfortably seated in seats 15 and the person operating the swing uses seats 16. The operator places both feet upon the pedal board 19 and alternately depresses and allows same to rise. When the swing is in a position of rest the chain 22 is retained at an angular position from its center line of gravity due to the platform overcoming the weight of the springs 21 and chain 22.

This difference in weight between platform 7 and chain 22 is equalized by foot pressure upon said pedal 19. Obviously rotating the latter about its pivot will move the entire platform rearward, so as to allow the swinging body to assume a new position about the changed gravitational center. As foot pedal 19 is allowed to rise the gravitational center is again changed inducing the platform 7 to swing forward again. As this operation is successively repeated the said platform will oscillate or swing front to rear in the familiar manner without the aid of external force.

It is to be understood that certain changes of construction can be made, such as the installation of an electrically operated crank

arm for swinging the platform, without departing from the spirit and scope of the invention.

I claim:—

5 A portable swing comprising a pair of supports movable upon a foundation, said supports including rigid uprights, a beam fixed between said uprights, an open frame disposed longitudinally between said up-
10 rights, a plurality of linked rod connections

between said frame and beam, seats interposed between adjacent pairs of said connections, a forwardly extending platform rigid with the center seat, a pedal hingedly engaged on said platform, flexible connections from the free end of said pedal to said beam, and springs interposed in the length of said flexible connections. 15

In witness whereof, I affix my signature.
JEREMIAH E. BROWN.
